SHAPING OF METAL TUBING

Frederick Cecil Draper, Sonorous Works, Deanbrook Road, Edgware, Middlesex, England
Filed May 7, 1956, Ser. No. 583,289
Claims priority, application Great Britain, May 11, 1955
6 Claims. (Cl. 29—157)

This invention relates to the formation of bends in tubing made of ductile metal and is particularly concerned with the treatment of such tubing in which the diameter is large in relation to the wall thickness. When tubing is bent on a former, the metal on the outside of the bend is placed in tension and is stretched while that on the inside of the bend, that is to say, on the other side of the neutral axis, is subjected to compressive forces. In general the wall of a pipe or tube is too thin to withstand such compressive stresses and unless precautions are taken will crumple and cockle.

One method of counteracting this effect is to subject the tubing to internal pressure so that before the bending takes place, the inner surface of the bend is in tension and consequently the superimposed compressive stresses produced by the bending serve only to cancel out the existing tensile stresses. Thus the resultant stress is in the region of zero and is not sufficient to produce cockling of the wall. As is well-known, the longitudinal stress produced by internal pressure is only half the circumferential or hoop stress so that when the internal pressure is increased to its maximum value, that is to say, corresponding to a value of hoop stress sufficient to produce yielding of the material, the longitudinal stress is only half this value. In theory this should be sufficient to prevent cockling of the inner surface of the bend because if the neutral axis is symmetrically placed in relation to the section, the tensile stresses produced in the outer surface will be equal to the compressive stresses produced in the inner surface. Consequently when the existing tensile stress in the outer surface produced by the internal pressure is increased from half the yield value up to the full yield value by means of the applied bending moment, the existing tensile stress in the inner surface should be reduced by a corresponding amount to substantially zero.

In practice, however, it is found that as soon as the outer surface begins to yield, the effect of work-hardening is to raise the yield point and consequently the neutral axis is no longer symmetrically placed, but moves outwardly of the section. Consequently a definite compressive stress is produced in the inner surface. Provided the ratio of the diameter of the tubing to the wall thickness is fairly low, the wall is able to resist this compressive stress and an effective bend can be produced. If, however, the ratio is larger, for instance, above about 35:1 then the inner wall cockles and the process is no longer effective.

According to the present invention, a length of tubing to be bent is subjected to mechanically applied tension and is forced into contact with a former having the required curvature in the plane of bending and shaped to support the tubing around approximately half its periphery. The tension is maintained at a value such as to avoid compressive stresses in the inner surface of the bend, which would produce cockling, and the outer surface of the bend is allowed to collapse inwardly under the tensile forces acting on it, after which the collapsed bent tubing is then expanded to its required final shape under the action of fluid pressure, while contained in a die.

At the start of the bending operation, the neutral axis is symmetrically placed in relation to the section of the tube, but as soon as the bending starts the tensile forces on the outer wall of the bend have an inward component which tends to force the wall inwardly. This

2

inward force is not resisted by internal pressure as in the process previously referred to and the wall accordingly starts to collapse. As a consequence of the change of section, the neutral axis is moved inwardly. As the bending continues the process is progressive, the outer wall gradually collapsing further inwardly and the neutral axis also moving inwardly. Naturally the closer the neutral axis approaches to the inner surface, the less the compressive stresses set up by the bending moment and consequently these can be fully compensated for by the mechanically applied tension so that the resultant stress in the inner surface of the bend is either tensile, or, if compressive, of such a small value as not to be sufficient to produce cockling.

It is found in practice that if the outer wall is allowed to collapse freely, that is to say, without the application of any internal pressure, it will move inwardly so as practically to come into contact with the inner wall to give a section which is approximately U-shaped. The result obtained is thus practically the equivalent of that described and claimed in the specification of Patent No. 2,748,455 except that instead of being brought about in a press as a preliminary step, the collapsing of the tube occurs naturally, merely as a result of the bending operation. The final stage is the same in both processes in that the tubing is expanded to its required final shape under the action of fluid pressure while contained in a die. The method in accordance with the present invention, however, has the advantages firstly that the bending and the collapsing of the tubing is produced as the result of a single operation and that in addition, if required, the former on which the bending is produced and which is shaped to support the inner surface of the bend, may constitute one half of the die used for the final stage of expansion. Thus once the tubing has been bent to shape on the former, it can be retained in position and parts constituting the remainder of the die may be brought up into register with the former so as to constitute the complete die.

If, as will generally be the case, the tubing is circular in cross-section, the surface of the former when seen in cross-section will be semi-circular so as to support the inner surface of the bend. During the collapse of the outer surface of the bend, the forces on the walls of the tubing tend to distort the tubing laterally so that if the cross-section of the former were to stop short at the limit of the semi-circle, the walls would tend to flow outwardly beyond the limit of the diameter. Preferably, therefore, the former is provided with parts which form continuations of the cross-section, these continuations extending either parallel to one another or diverging slightly to form a lead-in. The presence of the continuation parts then constrains the tubing and prevents the lateral distortion referred to. If the former is also to be used as half of the expansion die, then the continuation parts need to be formed as separate extension pieces which are removed before the remainder of the die is secured to the former.

In general a fixed former may be used and at the start of the bending operation the tubing is in engagement with the former at an intermediate point in its length, preferably its midpoint. The tubing is then forced into contact with the former along its length by appropriate movement of its ends, while maintaining the necessary tension throughout. As an alternative, however, the former may constitute part of a normal type of bending capstan to which the tubing is secured at one end, the other end being allowed to yield as the capstan turns, while maintaining tension. The use of a capstan is satisfactory for angles of bend up to approximately a right-angle, but if the angle is appreciably greater than this, the friction between the surfaces of the tubing and of

the former causes a progressive reduction of the tension along the length of the tubing. Thus although the tension may be at a sufficient value to prevent cockling at one end, it falls to a considerably lower value at the other end and this lower value may not be sufficient to prevent cockling. Thus if a bend of the order of 180 degrees is required, which is frequently the case, the previously mentioned method is preferred. The reason for this is that when the tubing is brought into contact with the former at an intermediate point and then both ends of the tubing are forced into contact with the former, the effect is the same as the production of two single bends, each of the order of ninety degrees. In this case the tension is a maximum at the two ends and decreases towards the middle, but does not reach a sufficiently low value for cockling to arise. This method has an additional advantage over the use of a capstan even for small angles of bend in that curves other than circular arcs can readily be produced. Whatever the curvature of the former, provided, of course, that it is not re-entrant, the tubing is forced into contact with it.

The invention will now be described in more detail by way of example with reference to the accompanying drawings, in which:

FIGURE 1 shows a length of tubing prior to bending;

FIGURE 2 is a diagrammatic illustration of the method of bending using a fixed former;

FIGURE 3 is a view of the tubing of FIGURE 1 after the initial bending but prior to the final expansion;

FIGURES 4 and 5 show two stages in the bending of a length of tubing on a capstan;

FIGURE 6 is a sectional view of the bent tubing on the line VI—VI in FIGURE 5;

FIGURE 7 shows a length of tapered tubing prior to bending;

FIGURE 8 shows the tubing of FIGURE 7 after bending and final expansion to shape;

FIGURES 9 and 10 show two stages in the operation of apparatus for carrying out the method of FIGURES 1 to 3;

FIGURE 11 is a sectional view of the tubing prior to bending seen on the line XI—XI of FIGURE 9;

FIGURE 12 is a sectional view of the tubing of FIGURE 11 after the initial bending operation; and

FIGURE 13 is a sectional view of the tubing after bending, seen on the line XIII—XIII in FIGURE 10.

Turning first to FIGURES 1 to 3, FIGURE 1 shows a length of parallel circular tubing 1 prior to bending. This tubing has tension applied to it mechanically by means of rams acting in hydraulic cylinders shown diagrammatically as 2 and 3, the connections to the ends of the tubing 1 being by means of collets 4 and 5 respectively. The tubing 1 is brought into contact at its mid-point with a former 6, which is on a fixed mounting. The former has the required curvature in the plane of bending, which in this case is a semi-circular arc. Moreover when seen in cross-section, the surface of the former is also semi-circular so as to support the inner surface of the tubing 1 as it is bent into the dotted position shown as 1'.

To achieve this result the hydraulic cylinders 2 and 3 are moved in the direction of the arrows to the position shown in dotted lines, thus forcing the tubing 1 into contact with the former 6. During this process the outer surface of the bend collapses inwardly as seen at 7 in FIGURE 3 for the reasons previously described. The hydraulic rams are allowed to float so that although they may be displaced within their respective cylinders, the tension in the tubing is maintained constant at a value which is sufficient to prevent the development of any appreciable compressive stresses in the inner surface of the bend. The collapsed tubing of FIGURE 3 then merely requires to be expanded to its final shape under the action of fluid pressure to give the finished product.

It is found in general that if the tubing is fully annealed before the start of the operation, it is possible

to bend the tubing while allowing the outer surface to collapse and then to expand the outer surface to its final shape in a single step without the need for any intermediate stages of annealing. By means of successive bending operations, compound bends, that is to say, bends in more than one plane, may be produced in readiness for the final step of expansion in a closed die. When a bend is required in the form of a circular arc of something less than 180 degrees, the method illustrated by FIGURES 4, 5 and 6, using a bending capstan may be employed. Here the tubing shown as 10 is secured at one end by means of a collet 11 to a former 12 mounted on a capstan 13, while at the other end it is secured by means of a collet 14 to a hydraulic ram acting in a cylinder 15. As the capstan is rotated from the position of FIGURE 4 to that of FIGURE 5 so the hydraulic ram is withdrawn from the cylinder 15 but the tension in the tubing is maintained constant. During the bending operation the outer surface of the bend collapses inwardly from the position 16', seen in dotted lines in FIGURE 6, to the position 16. From this figure it will be seen that the outer surface of the bend is practically in contact with the inner surface and that the tubing at this stage is approximately U-shaped in cross-section. The cross-section of the former 12 includes a semi-circular portion 17 which supports the inner surface of the bend. Beyond the semi-circular portion there are continuations 18 shown which diverge slightly to provide a lead-in for the tubing at the former turns. The main purpose of these continuations 18, however, is to prevent lateral distortion of the tubing beyond the limits of its diameter due to the outward components of the forces acting on it.

The tubing shown in the figures so far referred to is parallel, but the method in accordance with the invention is particularly applicable to the production of the various bends in wind instruments, and in general the tubing used for such bends is tapered as shown in FIGURES 7 and 8. FIGURE 7 shows the tubing 20 prior to bending, while FIGURE 8 shows the tubing after the formation of a bend of 180 degrees followed by the expansion step to give the finished product. FIGURES 9 and 10 show in more detail apparatus for bending the tubing of FIGURES 7 and 8 in accordance with the method of FIGURES 1 to 3.

The apparatus includes a base 21 provided with a circular table 22. This table supports a die 23 which is shaped to produce the bend of FIGURE 8. The former 23 is carried by an hydraulic ram 24 working in a cylinder 25 by means of which the former can be adjusted and can also be held in position during the final stage of expansion. The tubing 20 is held between collets 26 and 27 connected respectively to hydraulic rams working in cylinders 28 and 29. At the start of the bending operation, the cylinders 28 and 29 are situated diametrically opposite one another and apply the required degree of tension to the tube 20. With the tubing in this position the former 23 is moved into contact with the tubing under the control of the hydraulic cylinder 25.

The two hydraulic cylinders 28 and 29 are mounted to move in arcs, the centres of which lie in the region of the point of contact of the tube 20 with the former 23. As shown diagrammatically in the drawing, the cylinders 28 and 29 are guided by means of pins 30 and 31 working in arcuate slots 32 and 33 in the table 22. The cylinders are driven around the slots from the position of FIGURE 9 to that of FIGURE 10 by means of further hydraulic cylinders 35 and 36 respectively. These are pivoted beneath the base of the apparatus at 37 and 38 respectively and are connected to their respective pins 30 and 31 by means of connecting rods 39 and 40.

Before the start of the bending operation, an extension piece 45 is moved under the control of a further hydraulic cylinder 46 into the position shown in FIGURE 9 where it cooperates with the former 23. The purpose

of this extension piece 45 is to provide continuations, shown as 47 in FIGURE 11, of the cross-section of the former so as to prevent lateral distortion of the tubing as previously described. With the extension piece 45 in position, pressure is then applied to the hydraulic cylinders 35 and 36 to drive the cylinders 28 and 29 along their slots 32 and 33 so as to force the tubing 20 into contact with the former as shown in FIGURE 10. During this operation the two cylinders 35 and 36 rock about their respective pivots and as the cylinders 28 and 29 approach the end of their travel, the cylinders 35 and 36 rock back again until, as seen in FIGURE 10, they are in approximately the same angular position as in FIGURE 9, although, of course, the connecting rods 39 and 40 have been withdrawn into their respective cylinders.

During the bending operation, the outer wall of the tubing is allowed to collapse inwardly and it finally reaches the position shown in FIGURE 12. When the bending is complete, the extension piece 45 is withdrawn under the control of the cylinder 25 and is replaced by parts 50 and 51, which are moved inwardly under the control of hydraulic cylinders 52 and 53 respectively from the position of FIGURE 9 to that of FIGURE 10. These two pieces, together with the former 23, constitute a complete die for the final expansion of the tubing. The cross-section of this die is seen in FIGURE 13, from which it is clear that the part 51 fits into the space previously occupied by the extension piece 45 to constitute a die having an internal space of circular cross-section. Since this die is required to resist considerable internal pressure, it is important that the parts should be held securely in position and the angles of the three hydraulic cylinders 25, 52 and 53 acting at substantially 120 degrees to one another ensure that the considerable forces exerted by these cylinders are in equilibrium.

The pressure in the cylinders 28 and 29 is released to relieve the tension in the tubing 20, but the two cylinders still act to hold the inner surface of the bend firmly in contact with the corresponding surface of the die to prevent any risk of cockling during the subsequent expansion. Hydraulic pressure is then applied to the interior of the tubing 20 by means of a connection 55 leading to the collet 26. The effect of this internal pressure is to expand the tubing outwardly from the position shown in full lines in FIGURE 13 to that shown in dotted lines, and after this the parts of the die 50 and 51 may be withdrawn and the collets 26 and 27 disconnected to leave the finished product of FIGURE 8.

The hydraulic pressure required for the final expansion of the tubing, which is supplied to the connection 55, can be drawn from the same source of pressure as supplies the various hydraulic cylinders. The supply to the cylinders 28 and 29 is shown diagrammatically by way of the connections 56 and 57, but for simplicity the hydraulic connections to the other cylinders are not shown. It will be understood, however, that once the tube has been secured in position between the collets 26 and 27, the whole apparatus may be controlled by means of the various valves controlling the hydraulic pressure to the various components and that the com-

plete bending operation can be carried out in a very short space of time by means of an extremely simply sequence of steps by the operator.

I claim:

1. A method of forming a bend in a length of ductile metal tubing of substantially circular cross-section, comprising the steps of subjecting said tubing to mechanically applied tension, bringing said tubing into contact with a former, said former having the required curvature in the plane in which said tubing is to be bent and being shaped to support said tubing around approximately half its periphery, bending said tubing about said former while maintaining the tension in said tubing at a value which avoids compressive stresses in the inner surface of the bend in said tubing sufficient to produce cockling, but which causes the outer surface of the bend to collapse inwardly under the tensile forces acting on it and expanding the collapsed bent tubing to its required final shape under the action of fluid pressure while contained in a die.
2. A method according to claim 1, in which the former is employed as part of the die used for the final expansion.
3. A method according to claim 1, in which lateral distortion of the tubing beyond the limits of its diameter during bending is prevented by exteriorly supporting the lateral portions thereof as its inner surface approaches said former.
4. A method according to claim 3, in which the exterior support for the lateral portions of the tubing is withdrawn before the die is secured to the former before the final expansion.
5. A method according to claim 1, in which during the bending operation the former is fixed and the tubing is initially in engagement with the former at an intermediate point on its length, the tubing then being forced into contact with the former along its length by appropriate movement of its ends, while maintaining the tension.
6. A method according to claim 1 in which one end of the tubing is attached to said former and said former is turned while the other end of said tubing is yieldingly held with a force sufficient to maintain said tension.
